CARRIER FOR COILED RULER

David W. Goldman, Teaneck, N.J., assignor to Evans Rule Co., Elizabeth, N.J., a corporation of New Jersey

Filed Apr. 13, 1961, Ser. No. 64,716

Term of patent 14 years

(Cl. D52—1)

FIG. 1 is a front elevational view of a carrier for coiled ruler showing my new design;

FIG. 2 is a view looking downwardly on the carrier;

FIG. 3 is a side view thereof;

FIG. 4 is a side view taken from the side opposite that of FIG. 3;

FIG. 5 is a rear elevational view of the carrier; and

FIG. 6 is a view looking upwardly of the carrier of FIG. 5 and showing the bottom thereof.

I claim:

The ornamental design for a carrier for coiled ruler, substantially as shown and described.
